UNITED STATES PATENT OFFICE.

CONRAD WOGE, OF NEW YORK, N. Y.

KIT FOR SEWING OUTFITS OR THE LIKE.

Application filed April 11, 1927. Serial No. 182,748.

This invention relates to articles of manufacture and has for its object to provide a kit for sewing or knitting outfits which will be compact, durable and which can be conveniently carried in one's pocket or bag, without taking up much space.

In the accompanying drawing which forms part of this specification, Fig. 1 is a perspective view of the kit in natural size; 10 and Fig. 2 an enlarged longitudinal section on line 2—2 of Fig. 1.

Referring to the drawing more in detail, 10 denotes a kit of rigid material, such as wood, made in form of an oblong or egg shaped hollow body 10. This body is composed of two sections, one section constituting the main portion having a cylindrical bore 10', and the other being a segment 11 at one end thereof serving as a lid. This segment 11 is formed centrally on its inner face with a hollow cylindrical extension or shaft adapted when the sections are assembled to project into the cylindrical bore 10' of the main section. The part 12 of this extension 25 adjacent to the inner face of said segment or lid 11 is in form of a collar to fit snugly in the outer end of the cylindrical bore 10' and to frictionally hold said lid in closing position.

30 The other part of the cylindrical extension is provided on its circumference with two or more annular spaced flanges 13, 14 smaller in diameter than the collar 12 and forming spools for thread t . The said cylindrical extension is also provided with a central bore 15 which at its outer end is closed terminating in the segment or lid 11 and which is open at its inner end. This bore 15 serves as a receptacle for articles N such as needles, pins or the like. The open end of the bore 15 may be somewhat enlarged as at 15' to receive the end 16' of a cap or stopper 16 for said receptacle. At the end opposite the lid 11 the body 10 is provided with a longitudinal central bore 10² which extends clear through said body, forming an opening 10³ and terminating at its inner end in the cylindrical bore 10'. This bore 10² is of circular cross section gradually diminishing in

width toward the outer end 10³ so as to conform with the usual size and tapered shape of a thimble T and to serve as a socket therefore. Owing to the outwardly tapered shape of the socket the thimble could be inserted into it only from the inside of the casing 50 and cannot fall out through the opening 10³. In length the socket 10² is slightly smaller than the thimble and so admeasured that when the thimble is borne therein as shown it will rest with its open end against the inner end of said cylindrical extension of lid 11. The top of the thimble being exposed through the opening 10³ and thus accessible to the finger of the user, the lid 11 which tightly fits in the body 10 can be easily opened by pressing on said thimble.

What I claim is:

1. As an article of manufacture, a kit for a sewing or knitting outfit, comprising an open ended casing of rigid material, a lid 70 frictionally engaging one of the open ends of said casing, a cylindrical extension in said lid formed with a hollow open at one end, said extension being adapted to project into said casing and having annular flanges to 75 form spools for thread, the hollow of said extension serving as a receptacle for articles, such as needles or the like, a cap for closing the opening of said receptacle, and a socket at the open end of said casing conforming 80 in shape and size with a thimble so that the latter can be inserted only from the inside of said casing and can be moved inwardly to open the lid.

2. A kit for a sewing outfit or the like 85 comprising a casing open at both ends, a lid frictionally engaging one end of said casing and formed with a hollow extension adapted to project into said casing, the outer face of said extension serving as a spool for 90 thread and the hollow thereof serving as a receptacle for needles or the like, and means movably supported in the other end of said casing and adapted to normally bear against said extension, so that by pressing thereon 95 the lid will be removed.

In testimony whereof I affix my signature.
CONRAD WOGE.
